UNITED STATES PATENT OFFICE.

GEORGE W. KING, CHARLES B. KING, HARVEY T. GRACELY, AND HERBERT E. ROUSH,
OF MARION, OHIO, ASSIGNORS TO THE MARION STEAM SHOVEL COMPANY, OF
MARION, OHIO, A CORPORATION OF OHIO.

EXCAVATING-BUCKET.

1,050,838.

Specification of Letters Patent. Patented Jan. 21, 1913.

Application filed September 24, 1910. Serial No. 583,611.

To all whom it may concern:

Be it known that we, GEORGE W. KING, CHARLES B. KING, HARVEY T. GRACELY, and HERBERT E. ROUSH, citizens of the United States, residing at Marion, in the county of Marion and State of Ohio, have invented certain new and useful Improvements in Excavating-Buckets, of which the following is a specification, reference being had thereto in the accompanying drawings.

This invention relates to excavating buckets, and more particularly to that class of excavating buckets known as drag line buckets. Excavating buckets of this type are filled by being dragged over the material or bank to be excavated by means of a drag line and are then hoisted by means of a hoisting rope which is usually connected to the bucket at one side of the center of gravity by means of a bail. A suitable connection between the bail and the drag line enables the bucket to be maintained in such a position as to retain the load within the same during the hoisting operation by means of a pull on the drag line. In many of the buckets of this type now in common use a strong pull on the drag line must be maintained during the hoisting operation, and, in this manner, a heavy strain is imposed upon the drag line and its holding devices, causing these holding or friction devices to quickly wear out and necessitating their frequent replacement.

The object of this invention is to provide an excavating bucket of this type which can be supported in a position to retain the material therein during the hoisting operation by a very light pull on the drag line, thus eliminating both the annoyance and the expense due to the wearing out and consequent renewal of friction devices; and further to provide such a bucket which will be simple in its construction and positive in its operation, thereby enabling it to be manufactured at a small initial cost and to be maintained in operative condition with little or no trouble and expense.

It is a further object of the invention to provide the bucket with a four-point support, the points of connection of which with the bucket are adjustable to permit the bucket to be supported at different inclinations to the horizontal during the hoisting

operation; and also to so arrange the supporting members that during the filling operation these supporting members will exert a downward pressure upon the forward edge of the bucket, causing the same to bite into the material, thus enabling the bucket to be readily filled.

In the accompanying drawings, Figure 1 is a side elevation of a bucket, showing, in full lines, the bucket in filling position and showing, in dotted lines, the bucket in hoisting position; Fig. 2 is a side elevation of the bucket, showing the same in dumping position; and Fig. 3 is a front elevation of the bucket in filling position.

In these drawings we have illustrated one embodiment of the invention and have shown the same as applied to an excavating bucket 1 having a flat bottom and vertical side and rear walls. The front end of the bucket is open and hauling ropes 2 and 3 are connected to the forward ends of the respective side walls, converge forwardly and are connected at their forward ends to a drag line 4. In the bucket here shown the bottom terminates some distance in the rear of the forward ends of the side walls and the lower forward corners of the side walls are cut away. The hauling ropes, being connected to the forward ends of the side walls beyond the forward end of the bottom, will tend to depress the forward edge of the bottom and cause the same to bite into the material which is to be removed. This bucket is, however, only one of a number of types which can be employed in connection with the invention and it is not to be understood that the invention is in any sense limited to this particular type of bucket.

Two supporting members 5 and 6, respectively, are pivotally connected to the bucket in the front and rear of its center of gravity, respectively. In the present instance these supporting members are in the form of bails and have their arms pivotally connected to the vertical side walls of the bucket, the arms of the bail or supporting member 5 being connected to the side walls of the bucket in the rear of the center of gravity of the bucket and the arms of the bail 6 being connected to the side walls of the bucket in front of its center of gravity. The supporting member or bail 5 is connected

at its upper end with a hoisting rope 7. The upper or crosswise member 8 of this bail is preferably pivotally connected to the side members or arms thereof and has rigidly secured thereto an upwardly extending member 9 which is connected to the ends of the crosswise member 8 and braced against the same by inclined members or bars 10. The hoisting rope 7 is connected to the vertical member 9 in any suitable manner, the upper end of this member preferably extending above the upper ends of the inclined brace bars 10 to enable the rope to be readily secured thereto.

15 Suitable means are provided for operatively connecting the two supporting members 5 and 6 one to the other and this connecting means may be so controlled as to maintain the two supporting members in such relative positions as to support the bucket in its normal position, *i. e.*, in a position to retain the material within the same, or to allow the two supporting members to so alter their positions as to permit 25 the bucket to move about its point or pivotal connection to one of these members and thus discharge the load. This connection preferably comprises a lever 11 arranged after the manner of a toggle lever 30 and pivotally connected at one end to the upper transverse portion of the bail or supporting member 6, which bail is somewhat longer than its companion bail 5. The lever 11 is pivotally connected at a point between 35 its ends with the crosswise member 8 of the rear bail 5. The lower end of the lever which projects beyond the point of connection to the bail 5 has connected thereto a dumping rope 12 which passes through a 40 suitable guide 13 on the forward end of the bucket and is preferably connected with the drag line.

When the bucket is being dragged along the bank by means of the drag line the 45 weight of the supporting members will be thrown toward the front of the bucket and will cause the forward edge of the bottom to bite into the material and enable the bucket to be more readily filled. This is 50 particularly true when the bucket is being dragged down the side of a bank to fill the same as is frequently done with buckets of this character. As the bucket is filled and is being elevated by means of the hoisting rope 55 a sufficient tension will be maintained on the drag line and dumping rope 12 to hold the lower end of the lever 11 in its foremost position. When in this position the points of connection of the lever to the two supporting members will be slightly out of line with the hoisting rope and will not lock. The forward movement of the lower end of 60 the lever is limited by the upper portion of the bail 5 coming in contact with the upper 65 end of the lever, which serves to positively

prevent the lever being moved into a locking position, *i. e.*, with its points of connection to the two bails in alignment with the line of pull. The arrangement of the parts, however, permits the lever to be moved so close to the locking position that a very slight pull on the dumping rope 12 will maintain the same in position. When the lever is in this position, which is its normal position, the upper ends of the two supporting members are both connected with the hoisting rope and this rope is connected with the bucket at four points, thus forming a firm support therefor. The position of the bucket when the levers are operatively connected in this manner may be varied by altering the points at which the bails or supporting members are connected to the bucket, and, to this end, the side walls are provided on both sides of the center of gravity of the bucket with a series of holes 14 through any of which the connecting bolts for the bails may be passed. When the bucket has been elevated and transferred to the point where it is desired to dump the material the drag line 4 and dumping rope 12 are slackened off, thus releasing the lever 11 and permitting the forward supporting member or bail 6 to move downward under the pull exerted thereon by the load. The rear supporting member 5 will not materially alter its position other than it will be moved into a vertical position. Consequently, the bucket will move about its point of pivotal connection to the bail 5 and the forward or open end thereof will drop downward and cause the contents thereof to be discharged. When the bucket has reached a substantially vertical position the forward bail 6 will come into contact with the lower end of the rear bail 5. This contact will be more or less violent, as the downward movement of the bucket will be rapid. Consequently, the bucket will be jarred and the material will be loosened from the walls and bottom thereof so that all the material will be discharged, no appreciable quantity thereof adhering to the sides or bottom of the bucket. To fill the bucket it is permitted to move toward the ground in its dumping position, as shown in Fig. 2, and, as the forward end of the bucket approaches the ground or the material to be excavated, a pull is exerted on the drag line to cause the supporting members to move into their normal positions and to draw the bucket forward over the ground.

While we have herein shown and described one particular form of our invention it will be understood that this form is chosen for the purpose of illustration only and the construction and arrangement of the several parts of the device can be materially altered without departing from the spirit of the invention. For example, the

5 terms "hoisting rope," "dumping rope," etc., are used in a broad sense, and, although ropes are usually employed to accomplish the functions of these parts, it will be obvious that any other devices which will accomplish the desired results would be the full equivalents of the ropes. We, therefore, wish it to be understood that we do not desire to be limited to the details 10 of construction shown and described, for obvious modifications will occur to a person skilled in the art.

Having thus fully described our invention, what we claim as new and desire to 15 secure by Letters Patent, is:—

1. The combination, with a bucket, and a drag line therefor, of a supporting member for said bucket, a hoisting rope connected with said bucket, a lever connection 20 between said supporting member and said hoisting rope, and means for connecting said lever with said drag line, whereby the relative positions of said hoisting rope and said supporting member may be controlled 25 by means of said drag line.

2. The combination, with a bucket, and a drag line therefor, of a bail for said bucket, a hoisting rope connected with said bucket, a connection between said bail and 30 said hoisting rope comprising a lever, and a connection between said lever and said drag line, whereby the relative positions of said hoisting rope and said bail may be controlled by means of said drag line.

3. The combination, with a bucket, and a drag line therefor, of a bail for said bucket, a hoisting rope connected with said bucket, a lever connecting said bail with 40 said hoisting rope, and a dumping rope connected with said lever to control the relative positions of said hoisting rope and said bail.

4. The combination, with a bucket, and a drag line therefor, of a bail for said bucket, a hoisting rope connected with said bucket, a lever connecting said bail with 45 said hoisting rope, and a dumping rope connecting said lever with said drag line, whereby, the relative positions of said bail and said hoisting rope may be controlled 50 by means of said drag line.

5. The combination, with a bucket, and a drag line therefor, of a bail for said bucket, a hoisting rope connected with said bucket, a lever connected at one end with said bail and connected at a point between its ends 55 with said hoisting rope, and a dumping rope connected with the other end of said lever.

6. The combination, with a bucket, and a drag line therefor, of a bail for said bucket, a hoisting rope connected with said bucket, a lever connected at one end with said bail and connected at a point between its 60 ends with said hoisting rope, and a dump-

ing rope connecting the other end of said lever with said drag line.

7. The combination, with an excavating bucket, and a drag line connected therewith, of two supporting members pivotally connected to said bucket at fixed points in the front and rear of the center of gravity, respectively, a hoisting rope connected with one of said supporting members, an operable device connecting said supporting members, and a dumping line connected with said operable device and controlled by said drag line for manipulating said operable device to permit said bucket to move about its pivotal connection to one of said supporting 70 members. 75

8. The combination, with a bucket, and a drag line therefor, of two supporting members connected with said bucket, a hoisting rope connected with one of said supporting members, a lever connecting said supporting members, and means controlled by said drag line for manipulating said lever. 80 85

9. The combination, with a bucket, and a drag line therefor, of two supporting members connected with said bucket, a hoisting rope connected with one of said supporting members, a lever connected at one end to one of said supporting members and connected at a point between its ends with another of said supporting members, and a controlling member connected with the other end of said lever. 90 95

10. The combination, with a bucket, and a drag line therefor, of two supporting members connected with said bucket, a hoisting rope connected with one of said supporting members, a lever connected at one end to one of said supporting members and connected at a point between its ends with another of said supporting members, and a dumping rope connecting the other end of said lever to said drag line. 100 105

11. The combination, with an excavating bucket, and means for filling the same, of two supporting members pivotally connected to said bucket in the front and rear of its center of gravity; respectively, a hoisting rope connected with one of said supporting members, a lever connecting said supporting members one to the other, and means for maintaining said lever in a position to cause said supporting members to support said bucket normally in a position to retain the material therein and for permitting said lever to change its position, thereby permitting said bucket to move about its pivotal connection to one of said supporting 110 115 members. 120

12. The combination, with an excavating bucket, and means for filling the same, of two supporting members pivotally connected to said bucket in the front and rear of its center of gravity, respectively, a hoisting rope connected with one of said supporting 125 130 members.

members, a lever connecting said supporting members one to the other, and a dumping rope connected with said lever.

13. The combination, with an excavating bucket, and a drag line connected therewith, of two supporting members pivotally connected to said bucket in the front and rear of its center of gravity, respectively, a hoisting rope connected with one of said supporting members, a lever connecting said supporting members one with the other, and a rope connecting said lever to said drag line, whereby the position of said bucket may be controlled by means of said drag line.

14. The combination, with a bucket, of two non-flexible bucket-supporting bails pivotally connected at fixed points to said bucket, a hoisting rope connected with one of said bails, an operative connection between said bails to cause said hoisting rope to exert an upward pull on both of them, a drag line connected to said bucket independently of said bails, and a dumping line connecting said drag line with said operative connection.

15. The combination, with a bucket, of two bails pivotally connected thereto, a hoisting rope connected to one of said bails, a lever connecting said bails one to the other, a drag line connected to said bucket, and a connection between said drag line and said lever, whereby, the movement of said lever may be controlled by means of said drag line.

16. The combination, with a bucket, two

bails connected thereto, one of said bails being of greater length than the other, a lever connecting the upper ends of said bails one to the other, a hoisting rope connected to one of said bails, and means for controlling the movement of said lever.

17. The combination, with a bucket, of two bails pivotally connected thereto in the front and rear of the center of gravity thereof, respectively, one of said bails being of greater length than the other, a hoisting rope connected with the shorter bail, a lever pivotally connected at its upper end to the longer bail and at a point between the same to the shorter bail, a drag line, and a dumping rope connected with said drag line and with said lever at a point below its point of connection to the shorter bail.

18. The combination, with a bucket, of two bails, means for adjustably connecting said bails to said bucket, a hoisting rope connected with one of said bails, a lever connecting said bails one to the other, a drag line connected to said bucket, and a dumping rope connecting said lever with said drag line.

In testimony whereof, we affix our signatures in presence of two witnesses.
